(57) **CLAIM**

The ornamental design for arms of spectacle frames, as shown and described.

DESCRIPTION

FIG. 1 is a front elevational view of the arms of spectacle frames showing our new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom view thereof; and,

FIG. 7 is a perspective view thereof.

Dot-dashed lines have been used in FIGS. 1-7 to show the boundaries of disclaimed portions of the drawings.
